CLAIM

I claim the ornamental design for an electronic input device, as shown and described.

DESCRIPTION

FIG. 1 is an upper right perspective view of an electronic input device;

FIG. 2 is a lower right perspective view thereof;

FIG. 3 is a front elevational view thereof;

FIG. 4 is a rear elevational view thereof;

FIG. 5 is a right side elevational view thereof;

FIG. 6 is a left side elevational view thereof; and

FIG. 7 is a top plan view thereof; and,

FIG. 8 is a bottom plan view thereof.

The upper left perspective view of the electronic input device is a mirror image of FIG. 1, and is therefore not shown. The lower left perspective view of the electronic input device is a mirror image of FIG. 2, and is therefore not shown.

The broken lines in the drawings define the bounds of the claim, which extends to the boundary but does not include the boundary.
